Inventor:

UNITED STATES PATENT OFFICE.

PHILETUS W. GATES, OF CHICAGO, ILLINOIS, ASSIGNOR TO MUMFORD MOLDING MACHINE COMPANY, OF JERSEY CITY, NEW JERSEY, A CORPORATION OF NEW JERSEY.

PLUNGER AND PISTON CONSTRUCTION FOR MOLDING-MACHINES.

1,188,063.

Specification of Letters Patent. Patented June 20, 1916.

Application filed December 18, 1915. Serial No. 67,607.

To all whom it may concern:

Be it known that I, PHILETUS W. GATES, a citizen of the United States, residing at Chicago, in the county of Cook and State 5 of Illinois, have invented certain new and useful Improvements in Plunger and Piston Construction for Molding-Machines, of which the following is a specification.

This invention relates to improvements 10 in plunger and piston construction for molding machines or the like.

The object of this invention is to provide a coacting cylinder and plunger utilizing oil or similar fluid for a direct actuating means, 15 together with air or other gaseous fluid to actuate the heavier fluid.

My invention resides in the specific arrangement and construction of the parts, as hereinafter set forth and described in 20 the specification and shown in the accompanying drawing, in which:

Figure 1 is a vertical section of my invention, a portion of the plunger being shown in elevation; Fig. 2 is a transverse 25 horizontal section taken along the line 2—2 of Fig. 1; and Fig. 3 is a plan view of the structure shown in Fig. 1.

Like numerals refer to like elements 30 throughout the drawings.

10 designates generally my cylinder provided with a movable base 12 secured thereto by screws 12^a, or the like, and peripherally flanged at 10^a to permit the attachment of the gland follower 13, the 35 same being secured thereto by screws 13^a, this construction constituting a well known form of stuffing box or gland. The cylinder 10 is further provided with the bolting flange 10^c with bolting apertures 10^d therethrough, see Fig. 2. An air inlet 10^e 40 is provided in the wall of the cylinder 10, and an air tube 14 is threaded thereinto to furnish a supply of air, steam, or the like. Reciprocally mounted in the cylinder 10 is 45 the plunger or piston 15 formed with the table portion 15^a at its upper extremity and internally chambered, as indicated at 15^b. The bottom of the plunger is provided with a threaded aperture into which is threaded 50 the plug 16 provided with the aperture 16^a.

Oil or similar fluid is carried in the chamber 15^b, the same constituting in effect a reservoir, and the same may flow from the chamber 15^b through apertures 16^a into the clearance space 10^f beneath the plunger 15. 55 An inlet 15^d leads through the wall of the plunger 15 to the chamber 15^b above the level of the oil or other fluid therein, as shown in Fig. 1. It will be apparent that air or similar operating fluid flowing through 60 passage 14 and through inlet 15^d will exert pressure against the heavier fluid and the top of reservoir 15^b and raise the plunger the oil flowing out from the chamber 15^b through aperture 16^a into the cylinder 10, 65 thereby operating to raise the plunger 15 in the cylinder. To insure flow of air into the chamber 15^b during the rise or in raised position of the plunger 15, I provide the longitudinal groove 15^e in the side wall 70 thereof, as shown in Figs. 1 and 2, the aperture or inlet 15^d opening from the top of this groove, as shown in Fig. 1. The groove 15^e is in communication with the inlet 10^e, as will be apparent and air flowing there- 75 through into the groove 15^e will flow from the latter through inlet 15^d into the chamber 15^b, as will be apparent. On the return stroke of the plunger the oil will flow through the restricted aperture 16^a into 80 chamber 15^b providing a dampening or dashpot action, the air being expelled through inlet 14.

While I contemplate using my invention in connection with molding machinery, I 85 do not wish my invention to be restricted to such use, nor do I wish it to be restricted to the embodiment of my invention shown and described, except as defined by the appended claims.

90 What I claim is:

1. In combination, a cylinder having an air inlet in one side thereof, a plunger mounted therein, said plunger being constructed with a fluid reservoir, and a fluid 95 duct leading to said cylinder beneath said plunger, said plunger being further provided with an air inlet leading to said reservoir and communicating with said cylinder air inlet. 100

2. In combination, a cylinder having an air inlet in the side thereof, a plunger mounted therein, said plunger being constructed with a fluid reservoir, and a fluid duct leading to said cylinder beneath said plunger, said plunger being further provided with an air inlet leading to said reservoir, and a duct or passageway pro-

viding communication between said cylinder and plunger air inlets.

In testimony whereof, I have subscribed my name.

PHILETUS W. GATES.
